UNITED STATES PATENT OFFICE.

ROLF THELEN, OF MADISON, WISCONSIN, DEDICATED, BY MESNE ASSIGNMENTS, TO THE CITIZENS OF THE UNITED STATES OF AMERICA.

DRYING APPARATUS.

Application filed September 12, 1924. Serial No. 737,369.

(GRANTED UNDER THE ACT OF MARCH 3, 1883; 22 STAT. L. 625.)

This application is made under the act of March 3, 1883, chapter 143 (22 Stat. 625), and the invention herein described and claimed may be used by the Government of the United States, its officers and employees, and by any person in the United States without the payment to me of any royalty thereon. I hereby dedicate the same to the free use of the Government and the people of the United States.

This invention consists in brief in subjecting the material to be dried to air currents whose path takes a spiral or helical direction in contradistinction to most drying processes in which the path of the drying medium lies more or less in a single plane. This spiral circulation produces a greater uniformity in the drying medium throughout the length of the drying chamber than it has been possible to secure heretofore.

It is well known that spiral circulations of certain types have been used heretofore, thus, for instance, Letters Patent No. 449,170, issued to Phillips on March 31, 1891, discloses a system of drying bricks or other similar material in which the air enters the drying chamber at one end and follows a spiral path through the chamber, finally being discharged to the atmosphere at the opposite end of the drying chamber. This type of circulation, which may be classed as an external circulation because the air is drawn from the outside, passes but once through the spiral path within the chamber and is then discharged to the outside atmosphere, is designed for and adapted to progressive systems of drying. In these systems the material to be dried enters the drying chamber at one end and is periodically or constantly moved toward the opposite end, emerging therefrom at the end of the drying process.

The present invention is limited specifically to compartment systems of drying. In these systems the material to be dried remains continuously in position in the drying chamber throughout the entire drying

period, the entire charge being loaded into the chamber at one time and likewise removed from the chamber at one time. This invention is further limited to internal circulation of the drying medium. In this type of circulation the principal movement of the drying medium is constantly throughout the same path, the drying medium being recirculated and used repeatedly. It is the common commercial practice at the present time in many compartment systems of drying to employ a circulation of the drying medium which is principally in vertical planes perpendicular to the longitudinal axis of the drying chamber. Except in so far as it is disturbed by outside influences, each particle of the drying medium moves continuously in one of these planes. No positive means are provided for producing any longitudinal circulation in the drying processes. It has been found in actual full scale commercial tests that it is not possible with these systems to maintain uniform drying conditions throughout the length of the drying chamber. This lack of uniformity is especially pronounced in the case of long chambers in which material of widely varying moisture contents and widely varying drying rates is being dried rapidly.

In those parts of the drying chamber in which the material to be dried has become dry first, the atmosphere becomes drier and hotter than in those portions of the drying chamber in which the material to be dried dries more slowly. The resulting condition is disadvantageous because it produces over-drying in certain portions of the material to be dried and under-drying in other portions. The present invention overcomes these difficulties by producing a certain amount of longitudinal circulation of the drying medium in addition to the normal circulation which is commonly called cross-circulation. This longitudinal circulation imposed upon the cross-circulation results in a spiral circulation as will become evident from the detailed description of the application of the

invention to two types of drying chambers.

The present invention does not limit itself to specified methods of producing either the cross-circulation or the longitudinal circulation, since its purpose can be equally well accomplished whatever the method of producing the circulation may be. For purposes of illustration and to make the operation of this invention clear to those skilled in the art, two typical applications are presented, the first one illustrated in Figures I and II, a ventilated natural draft compartment kiln designed for the seasoning of lumber and other wood products, and, second, 15 an internal fan compartment dry kiln, also designed especially for the seasoning of lumber and other wood products.

Figure I is a cross-sectional elevation of a 20 ventilated natural draft compartment kiln. Figure II is a longitudinal sectional elevation of the same kiln. Figure III is a cross-sectional elevation of an internal fan compartment kiln. Figure IV is a longitudinal sectional elevation of the same kiln. 25 Corresponding parts on the four figures are correspondingly lettered in so far as possible. Letters A to O, inclusive, apply to all four figures. Letters P, Q and R apply only on Figures I and II. Letters S to Z, inclusive, 30 and Nos. 1 and 2 apply only on Figures III and IV.

Referring to the figures, AA represent 35 piles of lumber to be dried. The individual boards in the pile are arranged with the long axis parallel to the longitudinal axis of the kiln and with the board faces horizontal. Suitable spaces provided between the layers of lumber permit the passage of the drying medium.

BB represent the walls of the drying 40 chamber.

CC are air inlet ducts.

DD are air inlet duct dampers.

EE are air outlet ducts.

FF are air outlet duct dampers.

GG are heating coils.

HH are steam spray lines.

II are bunks upon which the lumber rests.

JJ are the rails upon which the piles of 50 lumber are moved into and out of the drying chamber.

KK are rail supports.

L is a motor.

M is the motor pulley.

N is the belt.

O is the driven pulley.

P is the blower in Figure II.

Q is the suction duct in Figures I and II.

R is the discharge duct in Figures I 60 and II.

S is the line shaft in Figures III and IV.

TT are line shaft bearings in Figures III and IV.

UU are disc fans in Figures III and IV.

VV are cross ducts in Figures III and IV.

WW are plenum chambers in Figures III and IV.

XX are plenum chamber diffusers in Figures III and IV.

Y is the suction box in Figure IV.

Z is the pressure box in Figure IV.

1 is the reversing switch in Figure IV.

2 is the longitudinal duct in Figures III and IV.

The general arrangement of the kiln 75 shown in Figures III and IV is similar to that illustrated in my Patent No. 1,466,518, issued on August 28, 1923, with the addition of the part required to produce the spiral circulation which is the subject of this invention.

The two kilns illustrated in Figures I to 80 IV are intended to use a mixture of air and water vapor, hereinafter referred to as air, for the drying medium. Superheated steam can, however, be used as a drying medium with any change in design.

The kiln illustrated in Figure I and II follows present commercial practice rather closely, with the exception of the blower P 90 and the mechanism functioning with it. This blower may be of conventional design, the particular type to be used to be determined by the individual conditions surrounding the design. When comparatively high pressures are required a centrifugal 95 blower is indicated. When, on the other hand, the pressures required are very low, disc or propeller fans can be used to good advantage. The blower illustrated is of the 100 centrifugal type. It is driven from the motor L through the pulleys M and O and the belt N. A suction duct Q extends from one end of the kiln to the suction side of the blower and a discharge duct R extends from the pressure side of the blower to the other end of the kiln. When the blower is in operation it draws air from one end of the kiln and discharges it to the other end of the kiln, producing a longitudinal circulation. 110 This circulation, combined with the cross-circulation produced in the usual manner as will be described later, produces a resultant circulation of spiral form. The specific effect of this spiral circulation is a continual 115 mixing of the air from end to end of the kiln. This avoids the formation of hot spots and cold spots in the kiln and thus produces more uniform drying.

The detailed operation of the kiln shown 120 in Figures I and II is as follows:

After the kiln has been loaded and closed, the blower P is put into operation, steam is turned into the heating coil G, the temperature of the kiln is regulated and controlled by the control of the steam supply through the heating coils. This control may be manual or automatic as desired. Control of the humidity of the air in the kiln is secured 125 by the manipulation of the air inlet duct 130

dampers and the air outlet duct dampers and by regulation of the supply of steam to the steam spray lines. It is customary to open the dampers sufficiently to maintain the humidity below the desired point under ordinary lumber drying conditions. The atmosphere outside of the kiln contains less moisture per cubic foot than that within the kiln; therefore, the humidity of the air in the kiln can be reduced by mixing with it the air from the outside atmosphere. Air may enter the kiln through the air inlet ducts and escape from the kiln through the air outlet ducts.

Having secured the desired setting of the dampers the humidity of the air of the kiln may be raised by admitting steam to the steam spray lines, which discharge the steam downward as indicated in Figure I.

Control of this steam supply may be manual or automatic as desired. The steam sprays issuing from the steam spray line tend to produce a downward air circulation as indicated by the arrows. This circulation is intensified by the action of the heating coils which tend to make the air rise in the space between the rows of lumber piles and by the cooling effect of the evaporation of moisture from the wood. When the side walls of the kiln are exposed to the outside atmosphere the cooling effect produced by them also tends to increase the circulation of the air in the kiln. The resultant circulation, commonly termed cross circulation, is in the plane of Figure I and in the general direction indicated by the arrows. The discharge of air from the discharge duct is producing a slight plenum at the end of the kiln opposite the discharge end of the duct and the withdrawal of air throughout the suction duct Q produces a slight vacuum at the other end of the kiln. The obvious result is a movement of air from the plenum toward the vacuum. This longitudinal movement superimposed upon the cross-circulation I have termed the spiral circulation.

It is not anticipated that the resulting circulation will be true spiral nor is it necessary, to accomplish the purpose of the invention, that it be so. The principal purpose of the invention is to produce greater uniformity in the drying medium and this is accomplished satisfactorily even when the path of the air particles is not a true spiral.

The kiln illustrated in Figures III and IV follows very closely the detailed construction illustrated and described in my Patent No. 1,466,518, with the exception of the longitudinal duct, the suction box and the pressure box. The detailed construction of these is as follows:

The right hand fan U in Figure IV discharges into the pressure box Z when the direction of the air circulation is as indi-

cated by the arrows. This pressure box communicates with the longitudinal duct, and the air discharged from the fan passes through the longitudinal ducts into the suction box Y from which it is drawn through the disc fan U at the left hand of the kiln as illustrated in Figure IV. This action, coupled with the cross-circulation normally produced by the fans creates a longitudinal mixing of the air, which I have termed the spiral circulation. When the direction of rotation of the fans is reversed the direction of the air movement in the longitudinal duct is also reversed and the cross-circulation as illustrated by the arrows in Figure III is reversed. The pressure box Z is then under vacuum and the suction box Y under a slight pressure. Likewise, the plenum chambers WW are under a slight vacuum and the cross ducts V serve to conduct the air from the fans to the heating coils instead of from the heating coils to the fans. The detailed operation is similar to the operation of the kiln illustrated in Figures I and II. Control of temperature and humidity may be had in precisely the same manner. The method of producing the circulation is different from the one previously described in that the principal circulation is produced by means of disc fans. This operation is described in detail in my Patent No. 1,466,518, already referred to. When the circulation of the air is as indicated by the arrows in Figure III all of the fans except the left hand one, Figure IV, draw air from the heating coils through the cross duct. The air passes from all of the fans except the right hand one, Figure IV, into the plenum chambers through the plenum chamber diffusers upward between two rows of lumber piles, laterally outward and downward to the heating coils, as illustrated. The right hand fan, Figure IV, discharges into the longitudinal duct to the pressure box and the left hand fan, Figure IV, draws air from the longitudinal duct to the suction box. When the direction of rotation of the shaft and the fans is reversed the air movement through the longitudinal duct is from left to right and the direction of the circulation through the lumber is opposite to that illustrated in Figure III.

The longitudinal circulation produced by the action of the end fans as just described has precisely the same effect as the longitudinal circulation produced by the blower P in the kiln illustrated in Figures I and II. This effect is in brief the longitudinal mixing of the air in the kiln which results in a greater degree of uniformity of the air than can be obtained without such longitudinal mixing.

Having fully described this invention and shown how it can be applied in two typical instances, I claim as original:

1. In a dry kiln adapted to compartment operation, means for producing a spiral circulation of air in said kiln, and means for maintaining a uniform temperature and humidity throughout the kiln.

2. In a dry kiln adapted to compartment operation, a blower, a suction duct, a dis-

charge duct adapted to withdraw air from the kiln at one end and to discharge said air into said kiln at the opposite end, and means for maintaining a uniform temperature and humidity throughout the kiln. ¹⁰

Aug. 12, 1924.

ROLF THELEN.
